UNITED STATES PATENT OFFICE.

SOLOMON R. WAGG, OF APPLETON, WISCONSIN.

PAPER-STOCK-SQUEEZING ROLLS.

933,604.

Specification of Letters Patent. Patented Sept. 7, 1909.

Application filed October 24, 1907. Serial No. 399,029.

To all whom it may concern:

Be it known that I, SOLOMON R. WAGG, a citizen of the United States, residing at Appleton, in the county of Outagamie and State of Wisconsin, have invented new and useful Improvements in Paper-Stock-Squeezing Rolls, of which the following is a specification.

This invention relates to paper stock squeezing rolls, particularly adapted for use in connection with what may be termed the main press in paper making machinery; and the object thereof is to provide means, in a manner as hereinafter set forth, which will overcome the sticking of the stock on the main press during the squeezing operation, thereby preventing waste of material, as well as breaks in the machine.

In paper making it is a fair estimate and well within the limits of actual experience to say that ninety per cent. of all breaks on paper-making machines occur on the first roll of the main press by what is known to the trade as "sticking on main press", meaning that the paper has broken down by sticking and breaking off on the main press. Under such conditions it is not uncommon for a mill to lose from fifteen to twenty-five per cent. in waste per day on a machine that has what may be termed "sticky stuff".

To overcome the foregoing objections is the object of this invention, which consists in providing what may be termed a main squeeze roll of smooth granite, a cushioning roll of softer material, or rubber, and a wool felt paper stock carrier, the carrier passing between the two rolls, the main squeeze roll of granite exerting pressure upon the stock, thereby expelling the moisture therefrom, and, owing to the nature of the surface of the main squeeze roll of granite it will materially prevent the stock from sticking to the roll.

A further object of the invention is to provide means in a manner as hereinafter set forth for connecting the granite roll to its spindle and journals, said means being such as to allow of the removal of the spindle of the granite roll when it becomes damaged, without the necessity of throwing the spindle or shaft away.

Further objects of the invention are to provide a paper stock squeeze roll which shall be simple in construction, strong, durable, largely overcoming any liability of the stock to stick and readily set up.

With the foregoing and other objects in view, the invention consists in the novel construction, combination and arrangement of parts hereinafter more specifically described and illustrated in the accompanying drawings, wherein is shown the preferred embodiment of the invention, but it is to be understood that changes, variations and modifications can be resorted to which come within the scope of the claims hereunto appended.

In the accompanying drawings, wherein like characters denote corresponding parts throughout the several views:—Figure 1 is a transverse sectional view showing the arrangement of the squeeze rolls in accordance with this invention, and also showing the woolen felt carrier provided with a layer of paper stock; Fig. 2 is an elevation partly in longitudinal section of the granite roll showing the manner in which the roll is connected to its spindle or shaft.

Referring to the drawings in detail, what may be termed the main squeeze roll is indicated by the reference character 4. The main squeeze roll has its periphery smooth and uninterrupted throughout and is constructed of granite having an axial bore 5 through which extends a hollow spindle or shaft 6. The shaft is of much less diameter than the axial bore 5, forming thereby a space between the shaft and the wall of the bore which receives a self-hardening cement, preferably brimstone, as at 7, for connecting the granite roll 4 to the spindle or shaft 5. The latter is of greater length than the length of the roll 4, projects from each end thereof and upon each projecting end is mounted a flanged journal bearing 8, the flange 9 thereof abutting against the ends of the roll and secured to the ends by the hold-fast devices 10 which extend through the flange and engage in the roll. The shaft 6 projects from each of the journals 8 and has screw-threaded end portions, as 11, upon each of which is mounted a clamping nut 12 which engages the journal 8. The nut 12 acts as a means to close one end of the space formed between the journal and the shaft 6. Openings 13 are provided in each of the journals 8 to allow of the self-hardening cement 7 to be supplied to the space formed between the shaft and the journals and between the shaft and the wall of the bore 5. The granite roll 4 is mounted in supports in a known manner and is approximately ver-

tically adjustable in a known manner with respect to the softer cushioning roll 14 which is arranged below and in approximately vertical alinement with the granite roll 4. The cushioning roll 14 is supported in a known manner and is connected to a suitable prime mover (not shown). The roll 14 consists of a core 15 of iron covered with a material softer than granite in any preferred manner such material being bronze, wood or rubber. It will be stated, however, that the cushioning roll may be constructed of any suitable material which would provide a cushion during the squeezing operation for the granite roll.

Extending between the rolls 4 and 14 is a carrier 20 formed of woolen felt and upon the carrier is positioned the paper stock 21 which, through the medium of the carrier 20, is carried between the rolls 4 and 14 so that the said stock 21 will be subjected to the action of the granite squeeze roll 4, thereby expelling the moisture or water therefrom.

During the passage of the stock between the two rolls and the expelling of the water or moisture from the stock, the stock will not stick to the smooth periphery of the granite roll, thereby overcoming the objection known to the trade as "sticking on main press".

When it is desired to remove the granite roll from its spindle, the spindle is heated in a known manner, say by way of example a hot rod extending in the hollow spindle. This renders the cement plastic and the granite roll can be moved from its spindle and a new one substituted.

What I claim is—

1. In combination a pair of spindles one arranged above the other and in vertical alinement, the upper of said spindles being hollow, a granite roll surrounding a portion of said spindle, a journal connected to each end of said roll, and a cement body capable of being liquefied interposed between the roll and spindle and the journals and spindles, said cement body adhering to the journals, roll and spindle whereby said elements are connected together.

2. A paper stock squeeze roll comprising a granite body portion, a spindle extending therethrough, a journal at each end of the spindle, and brimstone interposed between the roll and the spindle and between the journals and the spindle, said brimstone connecting the spindle, roll and journals together.

3. A paper stock squeeze roll comprising a stone body portion, a spindle for the roll, a flanged journal abutting at each end of the body portion and connected thereto, a self-hardening cement interposed between the body portion and the spindle and between the journals and the spindle, said cement

connecting the body portion, journals and spindle together.

4. A paper stock squeeze roll comprising a granite body portion, a spindle extending therethrough, journals upon the spindle, 70 said journals abutting against said body portion, and a liquefiable cement interposed between and adhering to the body portion and the spindle and interposed between and adhering to the journals and the spindle, said 75 cement connecting the body portion, journals and spindle together.

5. A paper stock squeeze roll comprising a granite body portion, a spindle extending therethrough, journals upon the spindle, 80 said journals abutting against said body portion, a liquefiable cement interposed between and adhering to the body portion and the spindle and interposed between and adhering to the journals and the spindle, said 85 cement connecting the body portion, journals and spindle together, and nuts mounted upon each end of the spindle, said nuts abutting against the journals and the cement.

6. A paper stock squeeze roll comprising a granite body portion, a spindle extending therethrough, journals upon the spindle, 90 said journals abutting against said body portion, a liquefiable cement interposed between and adhering to the body portion and the 95 spindle and interposed between and adhering to the journals and the spindle, said cement connecting the body portion, journals and spindle together, and nuts mounted upon each end of the spindle, said nuts abutting 100 against the journals and the cement, and each of said journals provided with means whereby the cement can be interposed between the body portion and the spindle and between the journals and the spindle. 105

7. A paper stock squeeze roll comprising a hollow spindle, a granite body portion mounted upon the spindle, a journal abutting against each end of the body portion and provided with a pair of flanges, means extending through a flange of each journal for connecting it to the body portion and a liquefiable cement interposed between and adhering to the body portion and the spindle and interposed between and adhering to the 110 journals and the spindle, said cement connecting the journals, body portion and spindle together. 115

8. A paper stock squeeze roll comprising a hollow spindle, a granite body portion mounted upon the spindle, a journal abutting against each end of the body portion and provided with a pair of flanges, means extending through a flange of each journal for connecting it to the body portion and a liquefiable cement interposed between and adhering to the body portion and the spindle and interposed between and adhering to the 120 journals and the spindle, said cement connecting the journals, body portion and spindle together. 125

spindle together, said journals provided with means whereby the cement can be interposed between the body portion and spindle and between the journals and spindle.

5. A paper stock squeeze roll comprising a hollow spindle, a granite body portion mounted upon the spindle, a journal abutting against each end of the body portion and provided with a pair of flanges, means extending through a flange of each journal for connecting it to the body portion, a liquefiable cement interposed between and adhering to the body portion and the spindle and interposed between and adhering to the 10 journals and the spindle, said cement con-

necting the journals, body portion and spindle together, said journals provided with means whereby the cement can be interposed between the body portion and spindle and between the journals and spindle, and nuts 20 mounted upon the spindle and abutting against the journals and said cement.

In testimony whereof I have hereunto set my hand in presence of two subscribing witnesses.
